Primary Examiner — Randall H. Gholson*(74) Attorney, Agent, or Firm* — Lowe Graham Jones PLLC(57) **CLAIM**

We claim the ornamental design for the reflective strip, as shown and described.

DESCRIPTION

FIG. 1 is a front view of the reflective strip.

FIG. 2 is a top view of the reflective strip.

FIG. 3 is a left side view of the reflective strip.

FIG. 4 is a right side view of the reflective strip.

FIG. 5 is a bottom view of the reflective strip.

FIG. 6 is rear a view of the reflective strip; and,

FIG. 7 is a perspective view of the reflective strip, shown in a preferred environment in which the reflective strip is clipped to a pocket of a representative shirt or other article of clothing, which is shown in partial cut-away view. Features illustrated in phantom lines are intended to show a preferred environment for the reflective strip and form no portion of the claimed design.
